UNITED STATES PATENT OFFICE

170,910

COMPARTMENTED PLATE

Charles J. Chaplin, South Portland, Maine, assignor to Chaplin Corporation, South Portland, Maine, a corporation of Maine

Application March 2, 1953, Serial No. 23,853

Term of patent 14 years

(Cl. D44—15)

To all whom it may concern:

Be it known that I, Charles J. Chaplin, a citizen of the United States of America, residing at South Portland, in the county of Cumberland and State of Maine, have invented a new, original, and ornamental Design for a Compartmented Plate, of which the following is a specification, reference being had to the accompanying drawings, forming part thereof.

In the drawings:

Fig. 1 is a bottom plan view of a compartmented plate, showing my new design.

Fig. 2 is a side elevation of said plate.

Fig. 3 is a top plan view of said plate.

I claim:

The ornamental design for a compartmented plate, as shown.

CHARLES J. CHAPLIN.
